UNITED STATES PATENT OFFICE

WILLIAM HENRY LOHMAN, OF WILMINGTON, DELAWARE, AND GEORGE WILLIAM KAESTNER, OF MONTCLAIR, NEW JERSEY, ASSIGNEES TO GENERAL CHEMICAL COMPANY, OF NEW YORK, N. Y., A CORPORATION OF NEW YORK

SHIPPING CONTAINER

Application filed September 27, 1929. Serial No. 395,576.

This invention relates to packages for the safe shipment of glass bottles and more particularly to that type of package in which the bottles are utilized for transporting corrosive liquids, such as acids, where the damage resulting from the breakage of bottles would extend to neighboring material. Bottle packages in actual use are subject to shocks incidental to transportation and storage which place considerable strain upon the glass bottles contained therein. The casing, as ordinarily furnished for use in such packages, supports the bottle at relatively few points and the result is that shocks due to handling are transmitted to the contained bottle at these points, the consequent concentration of forces resulting in frequent breakage.

Excelsior packing and other loose type packing has been used to cushion the bottles in the container, but it is our object to provide a cushioning device which is much neater and more efficient than excelsior, mineral wool, or other loose packing. More particularly, it is an object to provide an improved package in which the container comprises a bottom support which contacts with the bottom of the bottle in a manner more evenly to distribute transmitted forces due to the handling of the container and which automatically yields under shock to lessen the effect of the same on the supported bottle.

A further object is the provision of a cover for a container adapted to hold several bottles, this cover being provided with means projecting down into the container to retain the bottles in their respective compartments. The manner in which these objects are attained will appear from the description hereinafter given and the drawing forming part of this specification.

Referring to the drawing, wherein an example of the invention is illustrated, Fig. 1 is a plan view of the interior of a bottle package; Fig. 2 is a vertical section on the line 2-2 of Fig. 3, Fig. 3 in turn being a vertical section on the line 3-3 of Fig. 1.

The package comprises a receptacle 5 designed to hold ten bottles, but this number is arbitrary and can be increased or de-

creased as desired. The receptacle, which may be of wood or other suitable material, is reinforced at the ends by vertical battens 6 and horizontal handles 7. The interior of the receptacle is divided into compartments 55 for the reception of the bottles by means of a lattice formed by lattice strips 8 running parallel to the end of the case and lattice strips 9 running parallel with the side of the case. Attached to the bottom of the case are longitudinal spacers 11, to which in turn are attached by means of staples 12 the self-aligning bottom strips 13. It is on these bottom strips or supports 13 that the bottles rest, cushioned against shock. These strips, being mounted loosely by means of the staples 12 on the spacing strip 11, are free to turn slightly in a horizontal plane and are, furthermore, preferably hexagonal in shape so that they will automatically adjust themselves to fit more or less within the concave bottoms of the bottles. More particularly, the shape of the bottom strips is that of an irregular hexagon, two of the sides thereof, crossing the spacing strips, being longer than the other four. With bottom strips of this contour, the ends only of the hexagonal strips will contact with the concave bottom of the bottles. This contact will be made at points remote from the spacing strips aforementioned on which the hexagonal strips rest. It results that these ends, which project over the spacing strips and which clear the bottom of the receptacle by a distance equal to the thickness of the spacing strip, will receive the force of any impact transmitted to the bottles and will cause the bottom strip to rock on the spacing strip as a fulcrum.

There is thus provided a yielding support for the bottoms of the bottles which greatly minimizes the shocks incidental to transportation.

Corner blocks 14 are so placed as to lessen all side shocks which the case may receive. The compartments formed by the lattice strips 8 and 9 serve to hold the bottles in position within the receptacle but, to further reduce movement of the bottles with consequent jarring and danger of breakage, the cover 15 is provided with supports 16 to which is at-

tached the cover spring strip 17. This strip runs the length of the receptacle and, as will be seen from Fig. 3, is bevelled on the sides so as to contact with both the shoulders and necks of the bottles 18 in position in the receptacle. This limits both sidewise and vertical movement of the bottles, thus retaining them safely in their respective compartments, but without rigidity, due to the resilient nature of the spring strip 17.

In use, the receptacle as shown will hold ten bottles containing acid or other liquid and resting on the bottom supports 13. Bottles of the type ordinarily used have a circular concave bottom into which the hexagonal-shaped bottom support will project slightly, being further aided in this tendency by its freedom to move slightly in a horizontal plane by virtue of being attached only by one staple. It will be obvious that the more uniform contact between bottle and support thus provided will result in a distribution of the stresses transmitted to the bottles, as contrasted with the concentration of such forces where contact is limited to a few points on the bottom surfaces of the bottles.

Since the supports set into the concave bottoms of the bottles, these latter will be prevented from lateral movement at their lower ends and also, contact between support and bottle will be more uniform than is ordinarily the case where the support does not contact with the concave surface of the bottle. Furthermore, as the supports 13 project on either side of the spacers 11 and are attached to these spacers at only one point, an unbalanced force transmitted through the bottle will be received at the ends of the supports only and will cause the supports to rock on the spacer in a vertical plane relatively to the bottom of the receptacle. The support offered to the bottles is thus a yielding one which tends greatly to diminish the force of any shock transmitted to the receptacle and contents. Also, the structure which we have provided is simple, rugged and inexpensive in construction.

The cover of the receptacle is designed to aid in retaining the bottles in position in the receptacle. This effect is achieved by the pressure of a spring strip 17 suspended from the cover by means of trapezoidal vertical supports 16 as set forth above. Since the spring strip is bevelled on the sides contacting with the bottles, when the cover is set in place these bevelled sides contact with both the necks and the shoulders of the bottles, thus tending to hold them apart within the container and also to hold them down to prevent jumping and the consequent impact of the bottoms of the bottles on their supports. The spring strip runs the length of the receptacle, contacting with each bottle therein. By means of the combination of self-aligning bottom strips projecting upward into the

concave bottoms of the bottles and the ability of these strips to rock under stress, together with the cover spring strip tending to hold the bottles in position in the receptacle, a very safe and efficient package is produced where in bottles or other fragile containers may be transported with a minimum of danger of breakage or injury.

While the preferred form of the invention has been described about, it will be apparent that various changes in the specific form shown may be made within the scope of the following claim without departing from the spirit of the invention.

We claim:

A container for shipping a plurality of bottles comprising a rectangular case having rigid ends and sides, a rigid bottom and a rigid cover, longitudinally and transversely extending spacing strips located in said case and positioned to prevent lateral displacement of bottles packed in said case, members engaging said case and spacing strips to prevent displacement of said strips with respect to said case, a yieldable support for said bottles spaced from the rigid bottom of said case, said support permitting limited movement of the bottles with reference to the bottom of said case and a yieldable spring strip carried by the cover of said case and extending parallel with one of said spacing strips, said member being spaced from said cover and engaging the shoulders of bottles positioned within said case and resting upon said yieldable support to aid in positioning said bottles in said case.

In witness whereof we have hereunto set our hands.

WILLIAM HENRY LOHMAN.

GEORGE WILLIAM KAESTNER.
